(57) **CLAIM**

The ornamental design for a card box, as shown and described.

DESCRIPTION

FIG. 1 is a perspective view of a card box illustrating my new design;

FIG. 2 is a front view of the card box;

FIG. 3 is a rear view of the card box;

FIG. 4 is a left side view of the card box;

FIG. 5 is a right side view of the card box;

FIG. 6 is a top view of the card box;

FIG. 7 is a bottom view of the card box;

FIG. 8 is an exploded view of the card box of FIG. 1 that shows how a top portion, a middle portion and a bottom portion fit together; and,

FIG. 9 is another exploded view of the card box of FIG. 1 with the middle portion shown in an unfolded condition.

The broken lines in the drawings depict environmental subject matter only and form no part of the claimed design.
